UNITED STATES PATENT OFFICE.

NEWELL E. WHETSTONE, OF POLAND, OHIO.

COMBINATION SWING-CRADLE AND CRATE.

1,259,061.

Specification of Letters Patent. Patented Mar. 12, 1918.

Application filed October 12, 1917. Serial No. 196,145.

To all whom it may concern:

Be it known that I, NEWELL E. WHETSTONE, a citizen of the United States, residing at Poland, in the county of Mahoning, State of Ohio, have invented a new and useful Combination Swing-Cradle and Crate; and I do hereby declare the following to be a full, clear, and exact description of the invention, such as will enable others skilled in the art to which it appertains to make and use the same.

This invention relates to an improved combination swing and crate structure, and an object of the invention is to provide a device of this kind which is convertible from one to the other.

A further object of the invention is to provide a device of this kind comprising four longitudinal side pieces hingedly united and two end pieces, hingedly connected to the opposite ends of one of the side pieces, whereby either a swing chair as shown in Figure 1 or a crate as shown in Figs. 5 and 6 may be constructed.

A further object of the invention is the provision of an improved brace, utilized as shown in Fig. 1, for holding the longitudinal side braces relative to each other, when the parts are arranged to be used as a swing chair.

In practical fields the details of construction may necessitate alterations falling within the scope of what is claimed.

The invention comprises further features and combination of parts as hereinafter set forth shown in the drawings and claimed.

In the drawings:

Fig. 1 is a view in perspective of the combined crate and swing constructed in accordance with the invention.

Fig. 2 is a view in front elevation showing the swing chair utilized as a lawn swing.

Fig. 3 is a view in side elevation of the device as used in Fig. 2.

Fig. 4 is a sectional view on line 4-4 of Fig. 1.

Fig. 5 is an end view showing the structure arranged and utilized as a crate.

Fig. 6 is a cross sectional view through Fig. 5.

Fig. 7 is an enlarged detail view with parts in section of a brace.

Referring more especially to the drawings 1, 2, 3 and 4 designate four longitudinal side members, which are hingedly united as shown at 5, 6, and 7. The members 1

and 4 may in turn be hingedly united as shown at 8, when the said side members are arranged to be used as a crate. Hingedly connected to both ends of the side member 60 2, as shown at 9 and 10 are end pieces 11, which are provided with headed studs 12. The end pieces 11 are provided with additional studs 13 and 14. The opposite ends of the side members or pieces 1, 3 and 4, 65 are provided with flanges 15, 16 and 17, which overlap the end piece, particularly when the structure is arranged to be used as a shipping crate. However, when the structure is used as a swing chair, the flanges 70 15 are allowed to remain in overlapping engagement with the end pieces, and are held in such overlapping engagement by the pivoted hooks 18, which engage the headed studs 14. When the structure is used as a 75 swing chair the side pieces 3 and 4 are arranged as shown at Fig. 1, consequently they require reinforcing braces 19. The flanges 16 and 17 of the side pieces 3 and 4 have headed studs 20. These braces consist of the end and intermediate sections 21, 22, and 23, and also the turn buckle sections 24. The adjacent portions of the end and intermediate section have reduced threaded extensions 25, which are engaged 80 by the turn buckle sections 24. The intermediate sections of both braces have notches 26, and the outer ends of the sections 21 and 22 have notches 27 and 28. When the side pieces 3 and 4 are arranged as shown 85 in Fig. 1, the braces are applied, whereby the notches 26 may engage the headed studs 20 of the flanges 16 of the side piece 3, while the notches 27 and 28 may engage the headed studs 20 and 13 of the flanges 90 17 and the end pieces 11 respectively, after which the turn buckle sections may be set up and tightened so as to lock and reinforce the side pieces. The V-shaped suspension rods 29 are provided with hooks 30, 95 to engage the heads of studs 12, whereby by means of the springs 30^a (which engage the eyes 31 of the rods 29) the swing chair may be suspended on a porch. Upright supports 32 are provided. The supports consist of two sections 33 and 34 coupled together by the threaded sleeves 35. The sections 34 have bases 36, while the upper ends of the sections 33 have overhanging hooks 37. A rod 38 may be arranged so that its hooks 39 may engage the hooks 37. This rod 38 may pass through the eyes 31 of the 100 105 110

V-shaped suspension rods 29, as shown in Fig. 2, whereby the swing chair may be suspended between the supports 32, thereby allowing the swing chair to be utilized as a lawn swing, as shown in Fig. 2. When the structure is utilized as a shipping crate, the various parts, (which belong to the device as a swing chair) may be packed in the crate. In other words, the supports 32 may be knocked down, and their parts together with the V-shaped suspension rods 29 and the rod 38, the springs 30 and the braces 19 may be placed in the crate.

The invention having been set forth what is claimed as new and useful is:—

- 15 1. In a combined swing chair and shipping crate, a plurality of flat sections sequentially hingedly united whereby the sections may be arranged in stepped relations 20 and adjustable locking reinforcing braces for the opposite ends of three of the sections, and crate end sections hingedly united to the opposite end of one of the first sections.
- 25 2. In a combined swing chair and shipping crate, a plurality of flat sections sequentially hingedly united, whereby the sections may be arranged in stepped relations, one of said sections having a pair of end 30 sections hingedly connected to its opposite ends and provided with headed studs, two adjacent flat sections having their opposite ends provided with headed lugs and adjust-

able braces connecting the headed lugs of the adjacent ends of two of the flat sections 35 and the headed studs of the end sections, one of the first sections acting as a riser of the stepped relation having latch connections with said end sections.

3. In a combined swing chair and ship- 40 ping crate, a plurality of flat sections sequentially hingedly united, whereby the sections may be arranged in stepped relations, one of said sections having a pair of end sections hingedly connected to its opposite 45 ends and provided with headed studs, two adjacent flat sections having their opposite ends provided with headed lugs, and adjustable braces connecting the headed lugs of the adjacent ends of two of the flat sections 50 and the headed studs of the end sections, one of the first sections acting as a riser of the stepped relations having latch connections with said end sections, said braces comprising a plurality of axially aligned 55 members, turn buckles for axially connecting said members and adjusting them one toward the other, and means for suspending the swing chair.

In testimony whereof I have signed my name to this specification in the presence of two subscribing witnesses.

NEWELL E. WHETSTONE.
